UNITED STATES PATENT OFFICE.

HJALMAR SWANSON, OF CHICAGO, ILLINOIS, ASSIGNOR TO CUMMINS PERFORATOR COMPANY, OF CHICAGO, ILLINOIS, A CORPORATION OF ILLINOIS.

HAND PERFORATOR.

Application filed May 31, 1921. Serial No. 473,694.

To all whom it may concern:

Be it known that I, HJALMAR SWANSON, a citizen of the United States, residing in Chicago, in the county of Cook and State of Illinois, have invented a new and useful Improvement in Hand Perforators, of which the following is a specification.

This invention relates to hand perforators, and has for its object to provide a simply constructed though highly efficient device of this character which may be carried around upon the person of the operator, and which embodies, among other features, provision for punching data that is changed automatically at each operation of the perforator, the changeable data being preferably punched in combination with the punching of non-changeable data. By the invention, a salesman, for example, or other operator, may punch on successive slips of paper, such as sales tickets, different data on each ticket, as successive numbers which are changed automatically at each punching operation, the successive numbers indicating successive sales and being preferably combined with the punching of fixed data on each sales ticket to indicate the particular salesman making the sale. When employed in the manner above set forth, the invention provides perforating equipment that is especially suitable for large sales organizations, such as department stores, in that the use of the improved hand perforator will furnish a practically unalterable record of the sales made by each individual salesman.

In addition to the general objects recited above, the invention has for further objects such other improvements and advantages in construction and operation as may be found to obtain in the structures and devices hereinafter described or claimed.

In the accompanying drawings, forming a part of this specification and showing, for purposes of exemplification, a preferred form and manner in which the invention may be embodied and practiced, but without limiting the claimed invention specifically to such illustrative instance or instances:

Figure 1 is a side elevational view of a hand perforator constructed in accordance

with the improvements of the present invention;

Fig. 2 is a top plan view of the same;

Fig. 3 is a front elevation of the same;

Fig. 4 is a vertical sectional elevation taken longitudinally of the hand perforator;

Fig. 5 is a horizontal longitudinal sectional elevation of the same taken on the line 5—5 of Fig. 4;

Fig. 6 is another longitudinal horizontal sectional elevation taken on the line 6—6 of Fig. 4;

Fig. 7 is a transverse vertical section taken on the line 7—7 of Fig. 4;

Fig. 8 is another transverse vertical section taken on the line 8—8 of Fig. 4;

Fig. 9 is a detail view of one member of a locking mechanism hereinafter more fully described;

Figs. 10 and 11 are side elevational views of the hand perforator, partly in section, and illustrating the operation of the matrix changing mechanism and of the transfer of a carry operation from a lower order to the next higher order of the changeable data matrix rings; and,

Fig. 12 is a plan view of the said matrix changing mechanism.

The same characters of reference designate the same parts in each of the several views of the drawings.

In the illustrated embodiment of the invention, the hand perforator is especially designed for being used in the manner and for the purposes above specified and, for convenience, the present description will be confined to this use of the invention.

Features of construction of the hand perforator are, however, capable of other applications; hence, the scope of the invention is not confined to the specific use and specific embodiment herein described as an illustrative example.

Referring to the drawings: The hand perforator embodies in its construction a pair of movable jaw members 11 and 12 respectively provided, at one end with handle grips 13 and 14, and pivoted together, at the opposite end at 15. A spring 16, the opposite ends of which seat in sockets 17 and 18, 100

provided in the members 11 and 12, maintain said members normally apart from each other, a position in which the several punches are retracted from the dies. The sheet or 5 sheets of paper to be punched are inserted in an open slot 19, extending longitudinally in the jaw member 12. Situated in said member 12 at the bottom of the slot 19 is a die plate 20, the dies of which communicate 10 with an opening 21 below the die plate for the discharge of the punched articles of paper.

In the present instance, the die plate 20 is provided with two series of dies A and B, 15 the former co-operating with a series of punches for perforating the fixed data and the latter co-operating with a series of punches for perforating the changeable data. The fixed data dies A are furthermore divided into two groups a and a' for co-operation with corresponding groups of fixed data punches, each said group of punches co-acting with its corresponding group of dies to perforate a character of the fixed data, such as a digit of a two digit number 20 designating, for example, the particular person operating the punch. The changeable data dies are also sub-divided into two groups b and b' , each group co-operating 25 with a corresponding group of the changeable data punches to perforate a character.

The punches 22 are divided into two series A' and B'; and the series A', B' are respectively sub-divided into groups of punches 35 a^2 and a^3 and b^2 and b^3 ; the groups a^2 and a^3 co-operating respectively with the groups of dies a and a' , and the groups b^2 and b^3 co-operating respectively with the groups of dies b and b' in the manner above stated. 40 Both series of punches A' and B' extend into a chamber 23 provided in the jaw member 12, and the lower ends of said punches, when in advanced position with respect to their corresponding dies extend through a 45 perforate guide plate 24 located below the chamber 23 and forming the top of the paper receiving slot 19. When in the retracted position, the upper ends of the punches extend through a top guide plate 25, which 50 forms the top of the chamber 23. The punches 22 are further guided in their advancing or retracting movement, by a soft metal filling 26 located above the lower guide plate 24.

55 The punches A' of the fixed data series are operated by a fixed or non-adjustable matrix 27, which preferably consists of a plate fixed to the lower face of the jaw member 11 and movable to advance the fixed data punches 60 A' into their corresponding dies A, during the operation of squeezing together the handle grips 13 and 14 of the two jaw members 11 and 12. In the form shown, the matrix 27 is reversely socketed for each 65 group of punches a^2 and a^3 , so that it will

not operate those punches of the groups which are not required for perforating the particular characters desired. During the operative movement of the matrix 27, the punches not required pass idly through the 70 reverse sockets in the fixed matrix and only those punches which are required for punching the characters desired are engaged by the face of the matrix and advanced into co-operation with their respective dies. 75

The changeable data punches B' are operated by adjustable or revoluble matrices 29, there being one matrix for each group b^2 and b^3 of said punches B'. The adjustable matrices 29 are preferably constituted of rings which revolve upon a fixed arbor 30 secured in the bifurcated portion 32 of the jaw member 11. Each matrix ring 29 is preferably provided with a series of matrix faces 31, preferably ten in number, 80 one for each of the 9 digits and one for 0, the matrix faces 31 being also reversely socketed, so that they will not operate those punches of the group which are not required for printing the particular character desired. The matrix rings 29 are held in proper position for the operation of each of their matrix faces by positioning members 28 which are moved by springs 33 into one of a series of sockets 34 formed in the inner 85 circumferential portion of each matrix ring. When the positioning members 32 are seated within sockets 34 of their respective matrix rings, a matrix face 31 of each ring is in proper position for operating its corresponding group of changeable data punches. 90

In accordance with the invention, provision is made for changing the data punched by the series of punches B' on each operation of the perforator. In the present embodiment of the invention, which employs two matrix rings 29, one of said matrix rings 105 functions to punch digits of the units order, and the other functions to punch digits of the tens order. Consequently the tens order matrix ring is advanced one numeral space at each complete revolution of the units order matrix ring, that is to say,—whenever the units matrix ring is passing from "9" to "0". To accomplish this result, provision is also made for transmitting carrying impulses to the higher order matrix ring each time the lower order matrix ring passes from "9" to "0". Secured to each matrix ring 29 is a ratchet 35 having ten teeth 36, respectively companion to the digital matrix faces of their respective matrix rings. The ratchets 35 are prevented from rotating reversely by means of back stop pawls 37. 110 As shown in Figs. 10 and 11 the tooth 37^a, opposite the "9" matrix face of the units order matrix ring is cut deeper than the other teeth 37 of said units order matrix ring, the purpose of this construction appearing hereafter. Secured to the lower 115 120 125 130

jaw member 12 is an upright 38, which supports at its upper end a slideway 39. Working within said slideway 39, is a slide pawl 40, that is yieldingly urged toward the ratchets 35 by a spring 41 bearing against said pawl. The pawl 40 is provided at its forward end with a relatively long detent 42 for engagement with the teeth of the ratchet of the units order matrix ring and with a relatively short detent 43 for engagement with a tooth of the tens order matrix ring whenever a carry is to go over from the units to the tens order. The detent 42 is made long enough to engage a tooth of the units order ratchet at all times, and such engagement is effective to advance the units order matrix ring, one matrix face at the beginning of the operation of squeezing together the handle members 13 and 14 of the perforator. The other detent 43 of the pawl is, however, made too short to engage a tooth of the tens order ratchet, except when the tooth 37^a of the units order ratchet is positioned to receive the detent 42, which happens when the "9" matrix face of the units order ring is positioned for co-operation with the punches B'. The greater movement allowed the pawl 40 by such positioning of the tooth 37^a, brings the detent 43 forwardly into position for engaging and operating the ratchet of the tens order matrix ring, during the next operation of the perforator, thereby transmitting a carrying impulse to the tens order matrix ring. The completion of the carrying impulse, is accompanied by a movement of the tooth 37^a away from the detent 42, with the result that the detent 43 is again retracted into inoperative position, until a further complete rotation of the units order matrix ring has been effected to require the transfer of another carrying impulse. During the retracting movement of the jaws 11, 12 of the perforator, the detent or detents of the pawl 40 pass idly over the ratchet teeth 37.

Provision is also made for locking the hand perforator against further operation, when it has been operated to the limit of its capacity. Formed in the face of each matrix ring 29 is a transverse slot 44, the slots 44 of the respective rings being in alignment with each other, when the matrix faces are in position for punching the highest number that may be punched by the perforator, in the present instance, the number "99". Supported in a chamber in the upright 38 is a spring pressed stop pawl 45 which moves into the aligned slots 44 and prevents further rotation of the rings 29, as soon as said rings have arrived at the above designated punching position. The locking of the rings by the pawl 45 prevents setting of the perforator to begin another series of punching operations. Release of said rings is effected by means of a releasing

rod 46 rotatably mounted in the upper jaw member 11 and provided with a lug 47, which may, on rotation of the rod 46, be operated to engage and force the pawl 45 out of its locking position. The releasing rod 46 is preferably provided at its outer end with a perforate lock member 48, for co-operation with a fixed perforate lock member 49 secured to the side face of the upper jaw member 11. An ordinary padlock may be inserted into the holes of the locking members 48 and 49 to prevent the release of the pawls 45 and resetting of the matrix rings, except by one having the authority to do so. 60

In order to prevent accidental operation of the hand perforator, when carried about on the person of the operator, there is provided means for maintaining the jaw members 11 and 12 normally in their retracted 65 inoperative position. Pivottally secured to the lower handle grip 14 is an arm 51 which passes upwardly through a slot 52 in the upper handle grip 13. Near its upper end the arm 50 is provided with a shoulder 53 70 adapted to engage a lug 54 carried by the upper handle grip 13 for the purpose of maintaining the handle grips 13 and 14 and the jaws 11 and 12 normally retracted from each other. A spring 55 maintains the 75 shoulder 53 normally in engagement with the lugs 54. Whenever it is desired to operate the punch, the operator may by the movement of his thumb tilt the arm 50 forward slightly, so as to disengage the shoulder 53 from the lug 54, with the result that the arm 50 will pass freely through the slot 52 in the upper handle grip 13. 100

When pressure is released from the handles 13 and 14 of the jaw members 11 and 12, the spring 55 restores said jaw members to their retracted position. The movement of the members 11 and 12 to such retracted position is accompanied by a concurrent restoration of the previously operated punches of both series A' and B' to their normal position. For this purpose, each punch 22 is provided with a fixed collar 56, adapted to be engaged by the upper face of a perforate plate 57, through which 105 the several punches extend. The plate 57 is supported by side members 58 carried by the jaw member 11, and, as the latter moves away from the other jaw member 12, the plate 57 engages the collars 56 of the several 110 previously operated punches and restores them to their normal retracted position. 120

The invention as hereinabove set forth is embodied in a particular form of construction but may be variously embodied within 125 the scope of the claims hereinafter made.

I claim:

1. In a hand perforator, in combination: a pair of jaw members pivotally connected together; dies carried by one of said mem- 130

- bers and disposed in a series of fixed data dies and a series of changeable data dies; two series of punches respectively corresponding with the said two series of dies; a fixed matrix carried by the other jaw member for operating said fixed data punches; a plurality of revoluble matrix members also carried by said other jaw member and each provided with a plurality of matrix faces each of which may operate the changeable data punches; mechanism operable during movement of said jaw members for rotating said revoluble matrix members to change the positions of such matrix faces, and including means for effecting carrying transfers from one of said matrix members to the other; and means for locking said revoluble matrix members against operation, when the perforator has reached the limit of its capacity; substantially as specified.
2. In a hand perforator, in combination: a pair of jaw members pivotally connected together; dies carried by one of said members and disposed in a series of fixed data dies and a series of changeable data dies; two series of punches respectively corresponding with the said two series of dies; a fixed matrix carried by the other jaw member for operating said fixed data punches; a plurality of revoluble matrix members also carried by said other jaw member and each provided with a plurality of matrix faces each of which may operate the changeable data punches; and mechanism operable during movement of said jaw members for rotating said revoluble matrix members to change the positions of such matrix faces, and including means for effecting carrying transfers from one of said matrix members to the other; substantially as specified.
3. In a hand perforator, in combination: a pair of jaw members pivotally connected together; dies carried by one of said members; punches co-operable with said dies; a plurality of revoluble matrix members carried by the other jaw member and each provided with a plurality of matrix faces each of which may operate said punches; mechanism operable during movement of said jaw members for rotating said revoluble matrix members to change the positions of such matrix faces, and including means for effecting carrying transfers from one of said matrix members to the other; and means for locking said revoluble matrix members against operation, when the perforator has reached the limit of its capacity; substantially as specified.
4. In a hand perforator, in combination: a pair of jaw members pivotally connected together; dies carried by one of said members; punches co-operable with said dies; a plurality of revoluble matrix members carried by the other jaw member and each provided with a plurality of matrix faces each of which may operate said punches; and mechanism operable during movement of said jaw members for rotating said revoluble matrix members to change the positions of such matrix faces, and including means for effecting carrying transfers from one of said matrix members to the other; and means for locking said revoluble matrix members against operation, when the perforator has reached the limit of its capacity; substantially as specified.
5. In a hand perforator, in combination: a pair of jaw members pivotally connected together; dies carried by one of said members and disposed in a series of fixed data dies and a series of changeable data dies; two series of punches respectively corresponding with the said two series of dies; a fixed matrix carried by the other jaw member for operating said fixed data punches; a revoluble matrix member also carried by said other jaw member and provided with a plurality of matrix faces each of which may operate the changeable data punches; mechanism operable during movement of said jaw members for rotating said revoluble matrix member to change the position of such matrix faces; and means for locking said revoluble matrix member against operation when the perforator has reached the limit of its capacity; substantially as specified.
6. In a hand perforator, in combination: a pair of jaw members pivotally connected together; dies carried by one of said members and disposed in a series of fixed data dies and a series of changeable data dies; two series of punches respectively corresponding with the said two series of dies; a fixed matrix carried by the other jaw member for operating said fixed data punches; a plurality of revoluble matrix members also carried by said other jaw member and each provided with a plurality of matrix faces each of which may operate the changeable data punches; and mechanism operable during movement of said jaw members for rotating one of said revoluble matrix members to change the relative positions of the matrix faces of one matrix member with respect to those of another; substantially as specified.
7. In a hand perforator, in combination: a pair of manually-operable members pivotally connected together; dies carried by one of said members; a series of punches co-operable with said dies; a plurality of movable matrix means carried by the other member each having a plurality of matrix faces; and mechanism operable during movement of said members for operating said matrix means to change the relative positions of the matrix faces of one of said matrix means with respect to those of another; substantially as specified.
8. In a hand perforator, in combination: a pair of manually-operable members pivotally connected together; dies carried by one

of said members; punches respectively co-operable with said dies; ordinal matrix members carried by the other manually-operable member and each provided with a plurality of matrix faces; and mechanism operable during movement of said manually-operable members for operating said revo-

luble matrix members to change the positions of such matrix faces, and including means for effecting carrying transfers from one ordinal matrix member to the other; substantially as specified. 10

HJALMAR SWANSON.
